[57] CLAIM

[**] Term: 14 Years

The ornamental design for a face plate for oval tube hitch receiver, as shown and described.

[21] Appl. No.: 29/095,822

DESCRIPTION

[22] Filed: Oct. 30, 1998

FIG. 1 is a perspective view of the face plate for oval tube hitch receiver of the present invention shown in full line illustrated on an oval tube hitch receiver shown in phantom outline;

[51] LOC (7) Cl. 12-16
[52] U.S. Cl. D12/162
[58] Field of Search D12/162; 280/477,
280/507, 510, 511, 512, 513, 482

FIG. 2 is a rear elevational of the face plate for oval tube hitch receiver;

[56] References Cited

FIG. 3 is a right side elevational view thereof, the left side elevational view being a mirror image thereof; and,

U.S. PATENT DOCUMENTS

FIG. 4 is a top plan view thereof.

The broken line showing of a hitch receiver is for illustrative purposes only and forms no part of the claimed design.
